(57) CLAIM

The ornamental design for a disk cartridge, as shown and described.

DESCRIPTION

FIG. 1 is a front elevational view of disk cartridge showing my new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The broken line drawing of features on the disk cartridge shown in all views is for illustrative purposes only and forms no part of the claimed design.
